FACIAL STEAMING PAD

John Dopyera, Los Angeles, Calif.

Application November 13, 1935, Serial No. 49,501

3 Claims. (Cl. 128—163)

This invention relates to improvements in facial steaming pads.

The general object of the invention is to provide an improved pad for steaming a person's face, such as before shaving.

Another object of the invention is to provide a facial steaming pad which is formed to fit a person's face.

A further object of the invention is to provide a facial steaming pad including novel means for holding the pad.

Other objects and the advantages of the invention will be apparent from the following description taken in connection with the accompanying drawing wherein:

Fig. 1 is a face view of my improved facial steaming pad;

Fig. 2 is a view of the pad in an open position and including a filler member;

Fig. 3 is an end view of the pad shown in Fig. 1;

Fig. 4 is an enlarged section taken on line 4—4 of Fig. 1;

Fig. 5 is an enlarged section taken on line 5—5 of Fig. 1;

Fig. 6 is a view showing my facial steaming pad in use; and

Fig. 7 is a view similar to Fig. 1 showing a modified form of my invention.

Referring to the drawing by reference characters I have indicated my improved facial steaming pad generally at 10. As shown the device 10 includes two similar members, a front member 12 and a back member 13. The members 12 and 13 are made from a heavy cloth material, such as turkish toweling. Each of the members 12 and 13 are formed with a substantially V-shaped notch 14 in the upper edge thereof intermediate the width of the pad. From each side of the notch 14 the upper edges of the members 12 and 13 curve outwardly as at 15 and then incline downward as at 16 and have their sides bowed outwardly as at 17. The lower edges of the members 12 and 13 intermediate the width thereof are curved upward as at 18 and on each side thereof are curved downward towards the sides 17 as at 19. The peripheral edges of the members 12 and 13 are preferably bound by cloth tape members 20 which are stitched to their associated members as indicated at 21.

As clearly shown in Figs. 3 and 4 the material of each of the members 12 and 13 is formed into a protuberant portion 22 intermediate the width of the pad which forms a recess 23 in the rear face of the pad. As shown the pro-

tuberant portions 22 include tapered side walls 24 (see Fig. 3), an outwardly and downwardly inclined top wall 25, and a downwardly and inwardly inclined bottom wall 26 (see Fig. 4). Each of the members 12 and 13 have an aperture 27 therein intermediate their width adjacent the bottom of the notch 14 and in the top wall 25 of the protuberant portion 22. The edges of the apertures 27 are preferably bound with cloth tape 28 similar to the peripheral edges of the members 12 and 13.

The members 12 and 13 are secured together along the edges 15 thereof as by stitching them together with thread as indicated at 29.

The front member 12 is provided on its front face with cloth pocket forming portions 30 which along the edges 14, 15, 16, and 17 of the member may be secured thereto by the stitching 21. The lower edges 31 of the pocket portions 30 are free from the member 12 and are preferably bound by a cloth tape 32.

In use an operator positions his hands in the pockets 30 with the palms engaging the front face of the front member 12. The operator then immerses his hands and the pad in hot water and by squeezing his hands together wrings the pad out. Thereafter he places the pad 10 on his face with the chin positioned in the recess 23 and his nose positioned in the notch 14 and firmly presses the pad to the face as clearly shown in Fig. 6.

In Fig. 2 I have indicated an auxiliary filler member, for use with the pad 10, generally at 33. This filler member 33 is preferably made of the same material as the members 12 and 13 but of a lighter weight. The filler member 33 is shown as including two members similar to the pad 10, a front member 34 and a back member 35. The peripheral edges of the filler members 34 and 35 are formed to the same shape as the peripheral edges of the pad members 12 and 13 and like portions thereof are indicated by similarly primed reference numerals. The filler members 34 and 35 each include a pyramid portion 36 having an aperture 37 therein similar to the pyramid portions 22 of the pad 10. The filler members 34 and 35 are secured together along their edges 16' as by stitching 38.

When a filler member 33 is used, a plurality of snap-fastener members 39 are provided along the lower edge of the back pad member 13 and along the lower edge of the back filler member 35.

When the filler 33 is used the pad members 12 and 13 are opened as shown in Fig. 2 and the filler member 33 is secured thereto by the snap-

fastener members 39. The edges 16' of the filler member are then positioned adjacent the inner side of the pad edges 16 with the back filler member 35 engaging the inner face of the back pad member 13 and with front filler member 34 engaging the front face of the back filler member 35. The front pad member 12 is then folded down over the filler member with the inner face thereof engaging the front filler member 34. Thereafter the device 10 including the filler member 33 is used in the same manner as previously described. After the pad 10 and the filler member are used the filler member 33 is preferably removed from the pad by disengaging the snap-fasteners 39 and then the pad 10 and the filler member 33 are separately suspended from a suitable support to dry.

In Fig. 7 I have indicated a modified form of my invention generally at 40. In general the device 40 is the same as the device 10 except for the pocket members, and like parts thereof are indicated by similarly primed reference numerals. In the device 40 pocket forming portions 41 are provided on the outer face of the front pad member 12' and are secured to the pad member 12' along the edges 17', 19', and 42 with the pocket edges 43 towards the edges 16' unsecured. The pad 40 is particularly provided for barbers who generally work from the rear of a customer. From the foregoing description it will be apparent that I have provided a novel facial steaming pad which is simple in construction and highly efficient in use.

Having thus described my invention I claim:

1. A facial steaming pad, said pad including two members, a back member and a front member, each of said members being made of a cloth material having a substantially V-shaped notch in the upper edge thereof intermediate the width of said pad, said members being secured together at the upper edges on each side of said notch, the remainder of the edges of said members being free from each other, a filler, said filler member including a front member and a back member, said filler members each having a substantially V-shaped notch in their upper edges intermediate the width thereof, said filler members being secured together along a portion of their upper edges on each side of said notch portion, the remainder of the edges of said filler members being free from each other, one of said pad members and one of said filler members, including coacting fastening means for removably securing said pad and said filler together.

2. A filler, said filler member including a front member and a back member, said filler members each having a substantially V-shaped notch in their upper edges intermediate the width thereof, said filler members being secured together along a portion of their upper edges on each side of said notch portion, the bottom and sides of said filler members being free from each other, each of said filler members having an outwardly protruding pyramid portion intermediate their widths and positioned below said notch, said filler members each having an aperture therein adjacent the bottom of said notch and in said pyramid portion, said back pad member and said front filler member including coacting fastening means for removably securing said pad and said filler together.

3. A facial steaming pad, said pad including two members, a back member and a front member, each of said members being made of a cloth material having a substantially V-shaped notch in the upper edge thereof intermediate the width of said pad, a cloth tape arranged around the periphery of said members and stitched thereto, said members being secured together at the upper edges on each side of said notch, the remainder of the edges being free, each of said members having a forwardly protruding pyramid portion intermediate the width of said pad and positioned below said notch, said front and back members each having an aperture therein adjacent the bottom of said notch and in said pyramid portions, said pad on the front face of said front member having a pair of cloth pocket forming members secured thereto one on each side of said notch, a filler, said filler member including a front member and a back member, said filler members each having a substantially V-shaped notch in their upper edges intermediate the width thereof, said filler members being secured together along a portion of their upper edges on each side of said notch portion, the remainder of the edges being free, each of said filler members having an outwardly protruding pyramid portion intermediate their widths and positioned below said notch, said filler members each having an aperture therein adjacent the bottom of said notch and in said pyramid portion, said back pad member and said front filler member including coacting fastening means for removably securing said pad and said filler together.

JOHN DOPYERA.
